UNITED STATES PATENT OFFICE

ANTON MAREK, OF VIENNA, AUSTRIA, ASSIGNOR TO THE FIRM ČESKOSLOVENSKA ZBROJOVKA AKCIOVÁ SPOLEČNOST V BRNĚ, OF BRUNN, CZECHOSLOVAKIA

AUTOMATIC FIREARM

Application filed June 16, 1931, Serial No. 544,843, and in Czechoslovakia June 30, 1930.

This invention relates to automatic firearms with sliding barrel of the type in which accelerated backward movement is imparted to the breech mechanism by means of an impelling device after the disengagement of the breech from the barrel. In the hitherto known firearms of this type the accelerated backward movement of the breech mechanism is started suddenly, with the result that jolts and shocks are set up which impair the precision, produce deformations, and in many cases even cause fractures of parts of these firearms. The sudden acceleration also implies a rapid wearing of the controlling parts of the mechanism effecting this acceleration. The known types of firearms embodying impelling devices in which certain parts are resilient are open to the same objections, even if to a slighter extent.

The present invention has for its object to obviate entirely the occurrence of shocks and jolts and the further disadvantages incurred thereby in firearms with mechanically accelerated movement of the breech mechanism, this result being achieved, in accordance with the invention, by providing the impelling device with controlling and actuating means adapted to impart to the breech mechanism a backward movement in relation to the barrel, the velocity of which movement is increased from nought.

One example of the carrying out of the invention is illustrated in the accompanying drawings, in which:—

Fig. 1 shows the middle portion of a rifle with the parts of the mechanism in the position of rest, in longitudinal section.

Figs. 2 and 3 show the impelling lever of the impelling device, in front elevation (Fig. 3) and in side elevation (Fig. 2) as seen from left to right of Fig. 3.

Fig. 4 shows the bearing seating for the impelling lever, in longitudinal section.

Fig. 5 shows a section taken on the line V—V of Fig. 4.

Figs. 6 and 7 show the impelling device, in longitudinal section, in two different positions.

Fig. 8 shows graphically the movement set up by the impelling device.

Referring to Fig. 1, 1 denotes the sliding barrel; the rear guide for the barrel is denoted by 3. The barrel 1 is attached with its rear end to a casing 6 between the lateral walls 40, 41 of which the breech mechanism α is situated. The breech mechanism α consists essentially of a breech carrier 10 slidably mounted in guides in the casing 6, and of a breech 12 which is adapted to rock to and from the breech carrier, and which is fitted with the striking pin 13 and with the cartridge-extractor. The breech 12 is provided with a locking projection or catch 17 which cooperates with a locking surface 18 connected to and adapted to move with the barrel 1. In the constructional example shown in the drawings, the locking surface 18 is provided on the casing 6. The reference characters 19 and 20 denote controlling means provided on the breech carrier 10 and on the breech 12, which means, on cooperating, effect the rocking of the breech towards the breech carrier, and thereby the unlocking or disengagement of the parts 17 and 18. The reference characters 22 and 23 denote controlling means provided on the breech carrier 10 and on the breech 12, which means, on the closing of the breech, effect the rocking of the same away from the breech carrier and the engagement of the locking members 17 and 18.

The firearm is provided with an impelling device y which is adapted to impart an accelerated backward movement to the breech mechanism α after the disengagement of the latter from the barrel. In accordance with the invention the impelling device is provided with controlling means 30 and 31 which impart to the breech mechanism a backward movement in relation to the barrel the velocity of which movement starts at nought and is progressively increased. The controlling means 30, 31 can be constructed and arranged in a great variety of ways. In the constructional example shown, these controlling means consist of the impelling member 33 of the impelling device y , and of the controlling surfaces 30 and 31,

the latter being provided on the breech carrier 10; these controlling surfaces are so shaped and cooperate in such a manner that their resultant operating curve k (see Fig. 8) starts at a point at which there is no relative movement between the breech mechanism and the barrel.

The resulting curve of operation is denoted by k in the graphic representation given in Fig. 8. The y -axis relates to the movement of the barrel, and the x -axis to the accelerated movement of the breech mechanism in excess of that of the barrel. As can be seen from Fig. 8 the resulting curve of operation k starts at the point 0, that is to say at a point at which the acceleration is also nought. The resulting curve of operation k diverges gradually and increasingly away from the y -axis starting from the point 0, thus implying that the acceleration starts at nought, and gradually and constantly increases.

The impelling member 33 consists in the constructional example shown in the drawings, of a two-armed lever the axis of rotation of which is denoted by 35. As can be seen from the drawings, the controlling or actuating surface 30 provided on the impelling lever 33 begins at the center of rotation 35 of the impelling lever 33. Moreover, the controlling surface 31 provided on the breech mechanism touches the controlling surface 30 of the impelling lever in the axis of rotation 35 of the latter, both in the position of rest and until the commencement of the accelerated backward movement (see Fig. 6).

The impelling lever 33 is constructed with two arms. On the one of these arms the controlling surface 30 is provided. The second arm 36 of this lever is adapted to cooperate with a fixed surface 37 in the performance of its controlling or actuating function.

The impelling device γ is disposed beneath the barrel and between the downwardly projecting side walls 40, 41 of the casing 6. The bearing seatings for the impelling lever 33 are provided in these side walls 40, 41. The bearing parts provided on the impelling lever 33 and on the side walls 40, 41 are provided with recesses or cut-out portions of such shape that the impelling lever 33 can be inserted and removed from between the rigid side walls 40 and 41. In the constructional example shown the impelling lever is provided at both sides with segment-shaped annular projections 43 having their center at 35. The bearing parts on the side walls 40, 41 consist of segment-shaped annular grooves 44 the center of which likewise coincides with the point 35. When the impelling lever 33 is inserted in position, the annular projections 43 slide in the grooves 44, so that the impelling lever 33 rocks about the imaginary pivot-point 35.

Instead of being mounted in the above-described manner the impelling lever can also be mounted in the side walls 40, 41 by means of pins and pin-holes. In this case, however, the entire structure involved must be made wider, in order to ensure a good connection of the bearing parts (e. g. pins) with the impelling lever.

The impelling device γ is in the present example combined with a braking device α which serves for the braking and returning of the barrel into the position of rest. This braking device α consists of an arrangement of parts α' for braking and returning the barrel, and of an arrangement of parts α'' for damping the reflex movements of the sliding barrel set up by the restoring force and extending beyond the position of rest. In the example shown the braking device is linked up with the impelling lever 33. The impelling lever 33 is provided with a slot 50 traversed by a transverse pin 51 which is engaged by the hook-shaped end 53' of a rod 53 the other end 53'' of which is articulated by means of a joint 55 to an auxiliary piston 56. The braking spring 58 bears with its ends against two pistons 60, 61 arranged within a stationary cylinder 59. The piston 61 is constructed as a braking piston, and is fitted with a slotted spring braking ring 62 which is under compression in the cylinder, and thus presses against the inner surface of this cylinder 59 for the purpose of damping the reflex movements. The pistons 60, 61 are arranged between fixed stops 63, 64 on the cylinder, and in addition are themselves provided with stops 66, 67, of which the stop 66 cooperates with the auxiliary piston 56, and the stop 67 with the part 42 of the casing 6.

The point of attachment 51 of the braking device α to the impelling lever is so located, in the constructional example shown in the drawings, that, with the impelling lever in the position of rest, the line joining the point of attachment 51 and the axis of rotation 53 lies in the direction of the braking or of the restoring force. In the example shown, when the parts concerned are in the position of rest, the points 55, 51, and 53 lie in one line. In this manner the brake is caused to be supplementarily loaded, during the impelling movement of the impelling lever, this supplementary straining of the brake spring being initiated not suddenly, but gradually and starting from nought.

In the position of rest the parts occupy the positions in which they are shown in Figs. 1 and 6. The controlling surfaces 30, 31 are in contact with each other in the axis of rotation 35 of the impelling lever 33; the braking device α is likewise at rest, the pistons 60, 61 being in contact with the fixed stops 63, 64, while the auxiliary piston 56

touches the stop 66 on the piston 60, and the wall 42 of the casing 6 touches the stop 67 on the piston 61. On the firing of a shot the barrel is driven backwards in the direction of the arrow p by the force of the recoil. Together with the barrel the casing 6, the breech mechanism x , and the impelling device y also slide back. The auxiliary piston 56 is likewise drawn in the direction of the arrow p by the tension rod 53, and takes the piston 60 along with it, so that the spring 58 is caused to exercise its braking action. Up to the moment at which the surface 36 on the impelling lever comes in contact with the fixed counter-surface 37, the parts 1, 6, x , and y do not alter their respective relative positions. From the moment at which the surfaces 36 and 37 come together on, a supplementary backward movement starting at nought and gradually increasing in velocity is imparted to the breech carrier 10. This accelerated movement, since the controlling thereof starts at the imaginary pivot point 35 of the impelling lever 33, does actually commence at a velocity nought, and then gradually increases in velocity as shown in the diagram in Fig. 8. The stop surface 36 rolls around the stop surface 37, and thus rocks the impelling lever 33 which in its turn, through the cooperation of its controlling surface 30 with the controlling surface 31 on the breech carrier 10, jerks back the latter with an evenly accelerated movement. The backward movement of the barrel in the direction of the arrow p , and the subsequent rotating movement of the impelling lever 33 are braked by the increasingly compressed spring 58, this spring 58 finally causing the barrel and the impelling lever to be brought back into their initial positions. The breech carrier 10, which is thus moved with additional velocity in the direction of the arrow p , effects, through the cooperation of its oblique controlling surface 19 with the controlling surface 20, the disengagement of the interlocked parts 17, 18, since the breech 12 is thereby caused to rock towards the breech carrier 10, thus bringing the catch 17 out of engagement with the locking shoulder 18. After the disengagement of the parts 17, 18, the breech carrier 10 takes the released breech 12 along with it in the direction of the arrow p , until the breech action x , which is in a known manner under the action of a retracting spring, has reached the cocked position.

After the braking of the barrel 1 and of the impelling lever 33, the compressed spring 58, as already mentioned, causes the barrel and the impelling lever to be returned to their respective positions of rest. During this return movement in the direction of the arrow q , the impelling lever 33 rocks back into its position of rest, the surface 36 again rolling along the fixed stop surface 37. As soon as the surface 34 on the impelling lever comes in contact with the front wall 42 of the casing 6, the barrel 1 and the casing 6 are returned with the full force of the compressed spring 58. On the attainment of the position of rest the front wall 42 comes up against the stop 67 on the braking piston 61. At the same instant the damping device z'' comes into action, damping the reflex movements of the barrel 1 extending beyond the position of rest, and then bringing the barrel with the casing 6 finally into the position of rest. During the damping of the reflex movements the piston 60, in consequence of its contact with the fixed stop 63, remains at rest, while the auxiliary piston 56 detaches itself from the stop 66 and, independently of the piston 60, travels quite unchecked first in the direction of the arrow q and then in that of the arrow p . After the damping of the reflex movements, the barrel 1, the casing 6, the impelling lever 33, and the braking device z assume their respective positions of rest in which they are shown in Fig. 1.

The above-described automatic firearm is characterized by very great precision and long life, since, in consequence of the setting up of the accelerated movements of the breech action with a progressively increasing velocity starting from nought and of the gradually initiated additional loading of the braking spring by the impelling device, shocks and jolts are entirely obviated, and the moving parts are protected from wear and damage to the greatest possible extent. The construction described herein and illustrated in the accompanying drawings represents only one example of the many possible ways of putting the present invention into practice. The details of the described construction can be altered without departing from the scope of the invention. The actual construction of the breech mechanism, as also the manner of locking and releasing the breech, can be of any design, since they do not affect or form any essential part of the present invention.

I claim:

1. In an automatic firearm, a sliding barrel, a movable breech mechanism, a rotatable impelling lever, and a controlling surface on said lever for effecting accelerated movement of the breech mechanism, said controlling surface beginning at the axis of rotation of said lever.
2. In an automatic firearm as claimed in claim 1, a controlling surface on the said breech mechanism adapted, in the position of rest of the said firearm and until the commencement of the said accelerated movement of the said impelling member, to touch the said controlling surface on the

said impelling member in the said axis of rotation.

3. In an automatic firearm as claimed in claim 1, a controlling surface on the said breech mechanism adapted, in the position of rest of the said firearm and until the commencement of the said accelerated movement of the said impelling member, to touch the said controlling surface on the 10 said impelling member in the said axis of rotation, and the said impelling device being disposed beneath the axis of the said barrel.

4. In an automatic firearm as claimed in 15 claim 1, a casing attached to the said barrel, side walls on the said casing, said impelling lever being mounted between the said side walls and adapted to rotate about an imaginary axis of rotation, and a controlling 20 surface on the said breech mechanism, the said controlling surfaces being adapted to cooperate, and the said impelling device being disposed beneath the axis of the said barrel.

25 5. In an automatic firearm as claimed in claim 1, a casing attached to the said barrel, side walls on the said casing, bearing parts on the said side walls and lever, recesses in the said bearing parts adapted to enable the 30 said lever to be inserted between the said side walls and to be rotatable about an imaginary axis of rotation, and a controlling surface on the said breech mechanism, the said controlling surfaces being adapted to 35 cooperate, and the said impelling device being disposed beneath the axis of the said barrel.

6. In an automatic firearm as claimed in 40 claim 1, a casing attached to the said barrel, side walls on the said casing, portions of annular projections on the said lever, partial annular grooves in the said side walls, the said projections being adapted to engage in the said grooves, for the purpose 45 of enabling the said lever to be inserted between the said side walls and to be rotatable therebetween about an imaginary axis of rotation, and a controlling surface on the said breech mechanism, the said controlling 50 surfaces being adapted to cooperate, and the said impelling device being disposed beneath the axis of the said barrel.

7. In an automatic firearm as claimed in 55 claim 1 the combination with the said impelling lever of a device adapted to exercise a braking action upon the movement of the said barrel and to return the said barrel into the position of rest.

8. In an automatic firearm as claimed in 60 claim 1 the combination with the said impelling lever of a braking device comprising an arrangement of parts adapted to brake and to return the said barrel and 65 means for damping the reflex movements of the sliding barrel produced by the re-

storing force and going beyond the said position of rest.

9. In an automatic firearm as claimed in claim 1, the combination with said impelling lever of a device adapted to exercise a braking action upon the movement of said barrel and to return said barrel into the position of rest, means for connecting the said impelling device to the said braking device and for enabling the said braking device to be additionally strained during the impelling movement of the said impelling lever.

10. In an automatic firearm as claimed in claim 1, the combination with the said impelling lever of a braking device comprising means for braking and returning the said barrel and means for damping the reflex movements of the said sliding barrel produced by the restoring force and going beyond the said position of rest, means for connecting the said impelling lever to the said braking device and for enabling the said braking device to be additionally strained during the impelling movement of the said impelling lever, the said braking device being attached to the said impelling lever through articulating means on the said impelling lever.

11. In an automatic firearm as claimed in claim 1, the combination with the said impelling device of a braking device comprising means for braking and returning the said barrel and means for damping the reflex movements of the said sliding barrel produced by the restoring force and going beyond the said position of rest, means for connecting the said impelling lever to the said braking device and for enabling the said braking device to be additionally strained during the impelling movement of the said impelling lever, the said braking device being attached to the said impelling lever through articulating means on the said impelling lever.

95

100

105

110

115

12. In an automatic firearm as claimed in claim 1, the combination with the said impelling lever of a braking device comprising means for braking and returning the said barrel and means for damping the reflex movements of the said sliding barrel produced by the restoring force and going beyond the said position of rest, means for connecting the said impelling lever to the said braking device and for enabling the said braking device to be additionally strained during the impelling movement of the said impelling lever.

120

125

130

the said impelling lever, the said braking device being attached to the said impelling lever through articulating means on the said impelling lever, a recess in the said impelling lever, the said means of attachment of the said braking device to the said impelling lever being located within the said recess.

13. An automatic firearm according to claim 1, characterized in that said impelling lever is provided with two arms, one arm having a surface cooperating with a fixed rolling-off surface and the other arm being provided with said controlling surface.

14. In an automatic firearm as claimed in claim 1, a casing attached to said barrel and having side walls provided with segment-shaped grooves, and segment-shaped bearing members on said lever engaging in said grooves and permitting interchanging of said lever.

In testimony whereof I affix my signature.
ANTON MAREK.
